UNITED STATES PATENT OFFICE.

EDWARD SPURGEON, OF PLUMMER, IDAHO.

CURRENT-MOTOR.

1,290,391.

Specification of Letters Patent.

Patented Jan. 7, 1919.

Application filed July 19, 1916, Serial No. 110,253. Renewed May 15, 1918. Serial No. 234,780.

To all whom it may concern:

Be it known that I, EDWARD SPURGEON, a citizen of the United States, residing at Plummer, in the county of Benewah and State of Idaho, have invented certain new and useful Improvements in Current-Motors, of which the following is a specification.

This invention relates to an improved current motor and has as its primary object 10 to provide a device of this character which may be readily installed in a stream or river and adapted to derive a maximum power therefrom which may be utilized for commercial purposes.

15 The invention has as a further object to provide a device of this character employing a water wheel or current driven element which may be vertically adjusted with the rise and fall of the stream.

20 And the invention has as a still further object to provide a device of this character employing an improved arrangement for transmitting the power from the water wheel.

25 Other and incidental objects will appear as the description proceeds and in the drawings wherein I have illustrated the preferred embodiment of the invention and wherein similar reference characters designate corresponding parts throughout the several views,

Figure 1 is a side elevation of my improved current motor particularly showing the mounting of the water wheel,

35 Fig. 2 is a front elevation showing the arrangement of the water wheel within the supporting frame therefor,

Fig. 3 is a top plan view particularly illustrating the winding drum for adjustably 40 elevating the water wheel,

Fig. 4 is a fragmentary sectional view particularly showing the type of gear employed for transmitting power from the water wheel as well as the manner in which 45 the supporting frame of the device is formed to adjustably receive the bearing blocks for the water wheel,

Fig. 5 is a detail perspective view of one 50 of the bearing blocks of the water wheel and the bracket or shipper arm carried thereby for engagement with the worm of the vertical driving shaft of the device whereby

the said worm will be adjustably lifted as the water wheel is lifted,

Fig. 6 is a fragmentary plan view on a 55 slightly enlarged scale showing the adjustably mounted bearing for the upper end of the vertical driven shaft,

Fig. 7 is a fragmentary side elevation 60 more particularly showing the construction of the supporting frame of the said bearing.

Fig. 8 is a transverse sectional view illustrating the mounting of the bearing block 65 of Fig. 6 upon the supporting frame therefor,

Fig. 9 is a detail plan view of the adjustable bearing at the lower end of the said vertical driven shaft,

Fig. 10 is a fragmentary elevation showing the mounting of the drum of the water 70 wheel upon the supporting shaft therefor, and

Fig. 11 is a fragmentary detail perspective view showing one of the buckets of the water 75 wheel.

In carrying out the invention, I employ a supporting frame including spaced forward and rear uprights 10 and 11 respectively arranged in substantially rectangular relation and connected at their upper extremities, by cross pieces 12 and 13. The cross piece 13 is disposed at the forward side of the frame and projects at its extremities laterally, beyond the sides of the frame to receive braces 14 extending between the ends of the said cross piece and the uprights 11. The uprights 10 and 11 are set within a suitable base and extending from the base to the upper extremities of the uprights 11 are braces 15. Mounted upon the base in inward spaced relation to the uprights 10, are similar uprights 16 arranged substantially parallel to the uprights 10 and connected, at their upper extremities to the adjacent cross piece 12. Slidably mounted between the uprights 10 and 16 are bearing blocks 17 upon which is removably journaled a transversely extending shaft 18. Detachably mounted upon this shaft is a water wheel or current driven element.

The current driven element includes a drum 19 supported by spokes 20. These spokes are, as shown in detail in Fig. 10

of the drawings, received by sleeves 21 removably fitted upon the shaft 18 adjacent opposite ends thereof. Connecting the sleeves 21 with the said shaft, are set screws 22 which, at their inner extremities, are received within grooves in the shaft. Extending from the sleeves 21, are a plurality of radially projecting flanges 23 to which are bolted or otherwise secured, the spokes 20.

10 It will be observed that the spokes 20 are arranged in pairs and braces 24 extend between corresponding pairs of spokes at opposite sides of the drum. Mounted upon the drum 19 is an annular series of paddles or buckets 25 shown in detail in Fig. 11 of the drawings. These buckets are supported at opposite ends thereof by spokes 26 extending radially from opposite extremities of the drum. The spokes 26 at each side of 20 the drum are connected at their outer extremities as best shown in Fig. 1 of the drawings by an annular ring and supporting the said spokes, intermediate their ends, are a plurality of braces 27. Extending from 25 the spokes adjacent the braces 27 to the drum 19 are brace rods 28.

Mounted upon the uprights 10 adjacent the upper extremities thereof, is a transversely extending drum shaft 29 upon which is 30 fixed winding drums 30. Connected to these drums are cables 31 which, at their lower extremities, are attached to the bearing blocks 17 in the manner most clearly shown in Fig. 5 of the drawings. Upon one 35 side of the supporting frame is arranged a post 32 and journaled between the said post and the adjacent uprights 16 of the frame, is a shaft 33 upon which is mounted a sprocket 34 and a toothed wheel 35. Fixed 40 upon the adjacent extremity of the drum shaft 29 is a sprocket 36 and trained over the said sprocket and the sprocket 34 is a sprocket chain 37. Journaled upon the contiguous upright 10 of the frame adjacent the 45 toothed wheel 35 is a crank 38 which carries a pinion 39 meshing with the said wheel. A pawl 40 is provided for holding the toothed wheel against retrograde movement. As will now be understood, the crank 38 50 may be operated to turn the wheel 35 and wind the cables 31 upon the drums 30 for adjustably elevating the water wheel. In this connection, it should be stated that my improved device is designed to be erected 55 within a stream or river in such position that the current thereof will act upon the water wheel. The base for the supporting frame of the device may be suitably located in the bed of the river or stream adjacent a 60 bank thereof if desired and if found necessary, wings may be run from the forward side of the supporting frame upwardly and outwardly into the stream for directing the current's flow against the water wheel and 65 increasing the velocity thereof at the said

wheel. The purpose in adjustably mounting the water wheel will now be clear since it will be seen that the said wheel may be either raised or lowered as the level of the river or stream in which the device is mounted rises or falls. Thus, at all times, the water wheel may be maintained in active relation with respect to the stream. It is further to be observed that the buckets 25 will materially increase the effectiveness of 75 the water wheel since the said buckets will present obstructions to the current's flow of such nature that the current will effectually act against the said buckets to turn the wheel.

Fixed upon the outer end of the drum 19, is an annular face gear 41 having diamond shaped teeth 42 arranged for engagement with a worm 43 carried by a vertical driven shaft 44. The worm 43 is splined upon the 85 shaft 44 and is freely engaged by a shipper arm or bracket 45 carried by the adjacent bearing block 17 of the shaft 16. Consequently, when the blocks 17 are adjustably elevated, for positioning the water wheel 90 with respect to the stream, the worm 43 will be moved longitudinally upon the shaft 44 to coöperate with the face gear 41.

The shaft 44 is, at its upper extremity, received by an adjustable bearing 46 shown 95 in detail in Figs. 6, 7 and 8 of the drawings and is adjustably supported at its lower extremity by a similar bearing 47 shown in detail in Fig. 9. The bearing 46 includes a rectangular frame 48, the sides and ends 100 of which are formed of angle members suitably connected at their extremities. Connecting the sides of the frame with the uprights 10 and 11 upon the outer side of the main supporting frame of the device, are 105 bolts or other suitable fastening devices 49 having the heads thereof projecting into the bearing frame. Slidably mounted between the sides of the frame 48 is a bearing block 50 having longitudinally extending 110 grooves formed in opposite sides thereof to freely receive the heads of the bolts 49 in the manner best shown in Fig. 8 of the drawings with the said bolt heads adapted to hold the block 50 against vertical movement. 115 The block 50 rotatably receives the upper extremity of the shaft 44 and screw threaded into the ends of the block and adjustable upon the ends of the frame 48 are set screws 51. The bearing 47 includes a rectangular frame 52 also composed of angle members connected at their extremities. This frame is rested upon the base for the device and slidably receives a bearing block 53. The lower extremity of the shaft 44 120 is suitably journaled in and supported by the block 53 and an oil cup 54 is connected to the block for lubricating the bearing of the said shaft. Screw threaded into opposite ends of the block 54 and adjustable 125

through the ends of the frame 52 are set screws 55. The set screws 51 and 55 are arranged at right angles to the annular gear 41 upon the drum 19 of the water wheel 5 and as will now be seen, by properly adjusting these set screws, the shaft 44 may be positioned relative to the said gear for regulating the engagement between the worm 43 and the said gear.

- 10 Keyed or otherwise secured upon the lower extremity of the shaft 44 is a face gear 56 similar to the gear 41. The gear 56 is arranged to mesh with a worm 57 carried by a horizontal driven shaft 58. The 15 shaft 58 is supported by a plurality of suitable bearings 59 mounted upon the base for the device and keyed or otherwise secured upon the said shaft, is a pulley or other suitable power transmitting device 60. 20 As will now be seen in view of the previous description, the rotary movement of the water wheel will be communicated to the shaft 58 and a belt may be connected to the pulley 60 for transmitting the power from 25 the said shaft to be used for commercial purposes. I thus provide a very effective arrangement for the purpose set forth and a construction which may be easily installed and operated at minimum cost.

Having thus described my invention, what 30 I claim and desire to secure by Letters Patent is:

The combination of a supporting frame comprising spaced parallel posts, bearing blocks slidably mounted between and engaging said posts, a shaft carried by said bearing blocks, a water wheel mounted on said shaft, means supported on the posts and connected with the bearing blocks for raising and lowering the same and the water 35 wheel, a transmission shaft disposed vertically in the supporting frame adjacent the spaced posts at one side of the frame, an arm projecting from the bearing block at the said side of the frame, a gear fixed upon 40 the adjacent end of the water wheel, a gear meshing with said gear on the wheel and splined upon the vertical transmission shaft and engaged by the said arm whereby said gear will follow the raising and lowering 45 movement of the bearing blocks and remain in mesh with the gear on the water wheel, and gearing operatively connected with the lower end of said shaft for transmitting the power derived from the water wheel. 50 55

In testimony whereof I affix my signature.

EDWARD SPURGEON. [L. s.]
